Continuation-in-part of design application Ser. No. 11,917,
May 14, 1968. This application Sept. 5, 1969, Ser.
No. 19,030

Term of patent 14 years

Int. Cl. D7—01

U.S. Cl. D44—9

FIG. 1

FIG. 2

FIG. 1 is top plan view of a combined collapsible drinking cup and cover therefor showing my new design; and FIG. 2 is a side elevational view.

The characteristic feature of my invention resides in the specific ornamentation applied to the cover member.

This is a continuation-in-part of my earlier application, Ser. No. D. 11,917, filed May 14, 1968, and now abandoned.

I claim:

The ornamental design for a combined collapsible drinking cup and cover therefor, as shown and described.
